DESIGN FOR A CUP HOOK

Pierre F. Dover, Rye, N. Y., assignor to H. L. Judd Company, Inc., New York, N. Y., a corporation of Delaware

Application May 18, 1938, Serial No. 77,268

Term of patent 3½ years

To all whom it may concern:

Be it known that I, Pierre F. Dover, a citizen of the United States, residing at Rye, in the county of Westchester and State of New York, have invented a new, original, and ornamental Design for a Cup Hook, of which the following is a specification, reference being had to the accompanying drawing, forming part thereof, in which—

Fig. 1 is a side elevation;

Fig. 2 is a plan view; and

Fig. 3 is a section on the line 3—3 of Fig. 2, of a cup hook showing my new design.

I claim:

The ornamental design for a cup hook, substantially as shown.

PIERRE F. DOVER.
